(57) **CLAIM**

The ornamental design for a toilet brush and container, as shown and described.

DESCRIPTION

FIG. 1 is a top plan view of a first embodiment of toilet brush and container showing our new design;

FIG. 2 is a rear elevational view thereof;

FIG. 3 is a front elevational view thereof;

FIG. 4 is a bottom plan view thereof;

FIG. 5 is a right side elevational view of a second embodiment of a toilet brush and container showing our new design;

FIG. 6 is a left side elevational view thereof;

FIG. 7 is a rear elevational view thereof;

FIG. 8 is a horizontal cross-sectional view thereof, taken in the direction of line A—A of FIG. 7; and,

FIG. 9 is a top and front perspective view thereof.
